(57) **CLAIM**

The ornamental design for an animal toilet, as shown and described.

DESCRIPTION

FIG. 1 is a perspective view of an animal toilet showing my new design;

FIG. 2 is a perspective view thereof, with the ramp shown in an open position;

FIG. 3 is a front view thereof;

FIG. 4 is the rear view thereof;

FIG. 5 is a right side view thereof, the opposite side being a mirror image of the side shown;

FIG. 6 is a right side view thereof, with the animal toilet being extended, the opposite side being a mirror image of the side shown;

FIG. 7 is a first top plan view thereof;

FIG. 8 is a first bottom plan view thereof;

FIG. 9 is a second top plan view thereof, with the animal toilet being extended; and,

FIG. 10 is a second bottom plan view thereof, with the animal toilet being extended.

The features shown in broken lines in the Figures form no part of the claimed design.
